UNITED STATES PATENT OFFICE.

JACOB HOLBEN, OF ALLENTOWN, PENNSYLVANIA.

IMPROVEMENT IN OPERATING GRINDING-MILLS.

Specification forming part of Letters Patent No. 35,444, dated June 3, 1862.

To all whom it may concern:

Be it known that I, JACOB HOLBEN, of Allentown, in the county of Lehigh and State of Pennsylvania, have invented or discovered a new and useful Improvement in Operating Grinding-Mills; and I do hereby declare that the following is a full and clear description of the same and mode of operation.

My invention consists in the employment or use of sugar or other similar substance or substances for the purpose of cleaning millstones, enabling the stones to do more and better work than when cleaned in the usual manner, besides effecting a great saving of cost in the time and labor required to perform the operation.

The usual method of cleaning millstones is by pecking their surfaces with a sharp-pointed instrument, operated either by hand or machinery. In mills in constant use this operation of dressing has to be frequently performed, and always requires one or more of the stones to be removed from its bearings, (usually the upper one,) requiring extra labor for this purpose, besides consuming much time, which, with my improved method, is wholly saved.

To enable others skilled in the art to fully understand or practice my invention or discovery, I will proceed to describe it.

I run a small quantity of sugar or other similar substance, whether in a raw or refined state, into the eye of the upper stone while one or both of the stones (as the case may be) are in motion. The said substance passing between the stones is rapidly distributed over the entire surface thereof, and the result is that the stones are cleaned, and thereby made to cut with more ease than when cleaned in the usual or by any other method known to the public.

Instead of sugar or other substance being run into the eye of the stone, as before mentioned, the stones may be moved apart so as to allow the article to be spread over the surface

of one of them; or the application of the article may be made in any other way so long as the object sought to be attained is the same.

The sugar or other substance may be used in a liquid or dry state, the effect in either case being about the same. However, I prefer to use it in a liquid state—that is, by mixing the article with water or any other liquor in about the following proportions, namely: one pound of sugar or whatever other substance may be used to one gallon of water or other liquor. Different proportions will answer the purpose, though perhaps not as well as those which I have named. The sugar or other article being mixed and put upon the surfaces of the stones in the manner before explained, as the stones revolve it is distributed over the entire surface thereof, and acts to clean and restore their grinding action.

Some of the many advantages of this invention or discovery are—

First, the stones do not require to be moved from their bearings to be cleaned.

Second, the dressing or cleaning can be effected without stopping the mill.

Third, the cost of dressing or cleaning a pair of millstones is comparatively trifling in comparison with other methods, and when in good running order the stones will grind a third more flour before getting dull than when they are dressed in the usual manner.

Having thus described my invention or discovery, what I claim as new is—

The method herein specified of cleaning millstones.

The above specification of my improvements in operating grinding-mills signed this 13th day of March, 1862.

JACOB HOLBEN.
